UNITED STATES PATENT OFFICE.

OSCAR I. JUDELSHON, OF BROOKLYN, NEW YORK.

APPARATUS FOR CONTROLLING ELECTRIC CIRCUITS.

1,237,649.

Specification of Letters Patent. Patented Aug. 21, 1917.

Application filed July 10, 1915. Serial No. 39,182.

To all whom it may concern:

Be it known that I, OSCAR I. JUDELSHON, a citizen of the United States, and resident of New York city, borough of Brooklyn, in the county of Kings and State of New York, have invented certain new and useful Improvements in Apparatus for Controlling Electric Circuits, of which the following is a specification.

10 One of the objects of my invention is to provide simple and efficient means for controlling electric circuits, having special reference for operation in conjunction with means to apply a brake to a motor when the 15 current is cut off from the same, my invention being particularly applicable for use in conjunction with motors adapted to operate sewing machines and other machines where frequent stops are required.

20 A further object of my invention is to provide a casing or box to inclose the electric controlling devices and provided with a cover or door that is adapted to control means to prevent operation of the switch 25 arm of the apparatus in the event that the cover be left open.

A further object of my invention is generally to simplify and improve the construction of apparatus of the class specified.

30 My invention comprises novel details of improvement and combinations of parts that will be more fully hereinafter set forth and then pointed out in the claims.

Reference is to be had to the accompanying drawings forming part hereof, wherein,

Figure 1 is a front view of a controlling apparatus embodying my invention;

Fig. 2 is a side view thereof;

Fig. 3 is a view similar to Fig. 1, the cover 40 being open;

Fig. 4 is a vertical section substantially on the line 4, 4, of Fig. 5;

Fig. 5 is a vertical section substantially on the line 5, 5, in Fig. 1;

45 Fig. 6 is a vertical section substantially on the line 6, 6, in Fig. 1;

Fig. 7 is an enlarged detail substantially on the plane of the line 7, 7, in Fig. 2;

Fig. 8 is an enlarged sectional detail substantially on the plane of the line 8, 8, in Fig. 3, and

Fig. 9 is a side view illustrating my im-

provements supported in operative relation to a motor.

Similar numerals of reference indicate 55 corresponding parts in the several views.

In the accompanying drawings the numeral 1 indicates a casing, box or frame, which may be of any suitable construction, and which is shown provided with a cover 60 or door 2, hinged to the casing at 3, and adapted to close the open side of the casing. By preference, the cover 2 is hinged at the upper part of the casing so as to depend in front of the same to normally tend to 65 close the opening in the casing. As illustrated, the casing is adapted to be suspended from a support or table although the casing may be supported in any suitable manner.

At 5 is an electrical resistance shown in the 70 form of a wire wound upon insulating block 6, which may be secured within casing 1 by screws 7 in a wellknown manner. At 8 are a series of contacts carried by an insulating block 9, which may be secured within the 75 casing by screws 10 or in any suitable manner. The contacts 8 are in circuit with successive portions of the resistance, and for this purpose I have shown contact springs or strips 11 having their ends respectively in 80 engagement with corresponding adjacent portions of winding 5, which springs are shown held in place by the contacts 8. The contacts 8 are shown secured to insulating block 9 by means of screws 12 (Fig. 8) that 85 pass through said block and the springs 11 and securely bind said contacts and springs on the block. At 14 is a switch arm shown located within the casing and pivotally supported therein as upon the shaft 15 journaled in the casing. Arm 14 is shown provided with a contact 16 which is shown in the form of a plug slidable in an insulating bushing 17 in arm 14, (Fig. 8), and adapted to engage either of the contacts 8. A spring 90 18 is shown normally in engagement with contact 16 to maintain the latter in engagement with a contact 8, and spring 18 is secured to arm 14, as by a screw 19, the spring 18 and screw 19 being suitably insulated 95 from arm 14. I prefer the above stated construction for conducting current through spring 18 to contact 16, rather than to have the arm 14 in the circuit of the resistance.

90

95

100

At 20 is a spring shown coiled around shaft 15 and adapted to cause arm 14 normally to rest with contact 16 in engagement with one of the end contacts of the series of contacts 8, the arrangement shown being such that arm 14 is normally held against an adjustable stop 14^a on casing 1 by said spring. For this purpose one arm of spring 20 is shown bearing against screw 19 and another arm of 10 said spring is shown bearing against a terminal, such as a stud or screw 21 carried by and insulated from the casing. One of the lead wires for the circuit, such as a wire from the street plug, may connect with stud 15 or screw 21, as by a suitable binding screw 22 connected with stud or screw 21. By this means should the spring 20 become broken the circuit through the casing will be broken to avoid danger. At 23 is a contact 20 carried by and insulated from the casing, and secured thereto by a screw 24. Contact 23 is to be in electrical connection with a line wire, and as a convenience for this purpose I have shown said contact connected 25 by a conductor, such as a metal strip 25, with a binding post or screw 26 secured to and insulated from the casing, from which binding screw a wire may lead to one terminal of a motor 27, the other terminal of which 30 motor may be connected to the service wire. At 28 is a movable contact adapted to contact with contact 23. Contact 28 is carried by an arm 29 that is pivotally supported by the casing, as at 30, the contact 28 being 35 suitably insulated from said arm as by insulation at 31 (Fig. 7). At 32 is a spring coacting with contact 28 and shown connected with a post 33 carried by the casing, being shown supported by and insulated from a 40 lug 34 projecting from the casing. Spring 32 tends normally to cause contact 28 to engage contact 23. Post 33 is in electrical connection with the resistance 5 for which purpose I have shown a conductor, such as 45 a metal strip 35 secured at one end to post 33 by nut 36, and secured at the other end to a band 37 that is clamped upon an end portion of resistance 5. Band 37 is shown provided with opposing ears 37^a receiving 50 screw or bolt 38 which serves to clamp the band securely in electrical contact with an end portion of resistance 5 and to clamp strip 35 to the band. One of the contacts 11, such as the last of the series of such contacts, is shown in electrical engagement with band 37, being thus in circuit with an end portion of the resistance, while the other contacts 11 are directly in engagement with said resistance at spaced distances. By the 55 means described the strip 35 may be detached from post 33 or from band 37, whereby the resistance 5 may be readily removed from the casing without disturbing any connections, and, also, since the contacts 11 bear 60 65 by spring pressure against the resistance and

band 37, said contacts may be removed by merely removing block 9 without disturbing other connections. Of course, if preferred, the end contact 11 may be in direct engagement with resistance 5 instead of through band 37. Spring 32 is included in the circuit of the resistance and should said spring break, the circuit will be broken to avoid danger.

The operation of contact 28 is controlled 75 with the operation of arm 14, and circuit at 23, 28 is broken when arm 14 is at the normal position shown in Fig. 3, and contact at 23, 28 is closed just after arm 14 moves from its normal position and while the contact 16 is in engagement with the end contact 8, and the circuit remains closed while contacts 23 and 28 engage and any of the contacts 8 are engaged by contact 16. I have shown arm 14 pivotally connected at 80 39 with a link 40, that is shown passing through an opening 1^a in casing 1, behind the cover 2, which arm is provided with a projection 41 shown adapted to engage the under side of arm 29 to raise the latter to 85 break contact at 23, 28 when arm 14 returns to normal. Link 40 may be connected with any suitable device for operating arm 14, such as with a suitable treadle.

I provide means to prevent link 40 and 90 arm 14 from being operated in case the cover 2 is open, for which purpose I have shown a movable stop 42 pivotally supported at 43 within the casing, and located in such position as to extend under projection 100 41 if the cover 2 is open, as illustrated in Fig. 5. A spring 44 coacting with stop 42 and with the casing normally tends to retain stop 42 under projection 41. Said stop is shown provided with a pin or projection 105 45 adapted to engage cover 2, the parts being so arranged that when cover 2 is closed and pushes upon pin 45 the stop 42 will be pushed to one side of projection 41, as illustrated in Fig. 6, and so long as the cover is 110 closed the link 40 may be operated to actuate arm 14. At 46 is a spring-acting catch carried by the casing and adapted to engage the cover to retain it closed, to thereby keep stop 42 pushed back from projection 41. 115 This arrangement is of particular advantage in that should the operator leave the cover 2 open, he cannot operate arm 14, because stop 42 will then be under projection 41 and circuit must then remain broken at 23, 28, 120 since projection 41 cannot then be drawn down to allow arm 29 to descend, thereby requiring the cover to be kept closed in order to utilize the device. It will be understood that the break in the circuit at 23, 28 occurring when the greatest resistance is in the circuit reduces sparking at the contact 8 to 125 reduce its wear, it being a simple matter to replace contact 23 or 28.

In order to enable a brake to be applied to 130

a rotative element, such as a pulley or brake drum 47 of the motor, or to a machine driven by the latter, I provide an arm 48 that is shown adjustably supported at 49 upon a block 50, which is secured upon shaft 15, so as to rock toward and from element 47 as arm 14 rocks. Arm 48 is provided with a suitable brake shoe 51 adapted to coact with element 47. The arrangement shown is 5 such that when arm 14 is in the normal position (Fig. 3), the brake shoe will be moved into engagement with element 47 to check the rotation of the latter, and when arm 14 is swung downwardly (Fig. 3) the 10 shoe 51 will be raised from an element 47. In order to provide adjustment of arm 48 and the brake shoe with respect to element 47 I have shown screws 52 carried by an extension 50^a of block 50, beneath arm 48 on 15 opposite sides of the pivotal point 49, whereby said screws may be adjusted in the required direction to swing arm 48 on its pivot, and when said screws are set tight against the arm, the latter will be retained 20 in adjusted position. Block 50 is shown set in a recess in casing 1, whereby the wall of the casing may be integral.

With my improvements secured in position with brake arm in coactive relation to 25 the element 47, and the link 40 connected with a suitable treadle, the cover 2 must be closed in order to cause stop 42 to be removed from under projection 41 (Fig. 6). When link 40 is next drawn down and arm 30 14 is moved, the projection 41, by descending from under arm 29, permits contact to be closed at 23, 28, while contact 16 is in engagement with the first contact 8 of the series to include the greatest resistance in the 35 circuit. The circuit then will be from 21, through spring 20, 19, 18, 16, 8, the corresponding strip 11, thence through the resistance and band 37, through strip 35, post 33, spring 32, contact 28, to contact 23, and 40 thence through strip 25 to post 26, causing operation of the motor which is included in the circuit. As the arm 14 is drawn down to engage the several contacts 8, the resistance will be correspondingly cut out, and on the 45 return movement of arm 14 the resistance will be correspondingly cut in until, just before arm 14 comes to rest against stop 14^a and while contact 16 is in engagement with the upper contact 8, the projection 41 will 50 raise arm 29 and break the circuit at 23, 24.

While I have illustrated the resistance 5 wound upon the block or insulation 6 in a single winding, it will be obvious that the resistance may be provided in any other 55 wellknown manner, such as a plurality of separate coils connected in series to the contact 28, and each coil respectively connected to a contact 8, and that other changes may be made in the details of construction and ar-

rangements of parts set forth, without departing from the spirit of my invention. 65

Having now described my invention what I claim is:—

1. The combination of a plurality of contacts, resistance material connected with said contacts at spaced distances, a movable contact to coact with the first named contacts, a link connected with the movable contact to actuate the same, an arm mounted independently of the movable contact, a contact operated by said arm and connected to said resistance, a contact to coact with the last named contact, and means operative with said link to cause said arm to break the circuit of the last two named contacts when 70 said movable contact is in the normal position and adapted to permit said movable contact to successively engage the first named contacts while the said two contacts are in engagement, a casing for said parts, a movable cover for the casing, and means to prevent operation of said movable contact when the cover is open. 75

2. The combination of a series of contacts, resistance material in circuit with said contacts at spaced distances, a movable arm carrying a contact to successively engage the first named contacts, a link operatively connected with said arm, a second arm provided with a contact connected with said resistance, 90 a contact to coact with the last named contact, and means coactive between said link and the second arm to cause the latter to break the circuit at its contact when the first named arm contact is in engagement with 95 one of the first named contacts, a casing for said parts, a movable cover for the casing, and means to prevent operation of said movable contact when the cover is open. 100

3. The combination of a casing having a movable cover, a movable switch arm carried by the casing, a series of contacts, a resistance in circuit therewith carried by the casing, and means to prevent operation of said arm 105 when said cover is open. 110

4. The combination of a casing having a movable cover, a movable switch arm carried by the casing, a series of contacts, a resistance in circuit therewith carried by the casing, and a movable stop to prevent operation of said arm when the cover is open, said cover being adapted to hold the stop out of coaction with the arm when the cover is closed. 115

5. The combination of a casing having a movable cover, a movable switch arm carried by the casing, a series of contacts, a resistance in circuit therewith carried by the casing, a link connected with said arm and provided with a projection, a movable stop in coactive relation with said projection to prevent movement of said arm when the cover is open, a projection interposed be- 120 125

- tween the stop and cover to cause the stop to be held out of coaction with the projection of said link when the cover is closed, and means to retain the cover closed.
6. The combination of a casing having a movable cover, a movable switch arm carried by the casing, a series of contacts, a resistance in circuit therewith carried by the casing, a link connected with said arm and provided with a projection, a movable stop, a spring to hold the stop in coaction with said projection of the link when the cover is open, a projection interposed between the stop and cover to cause the stop to be held out of coaction with the projection of said link when the cover is closed, and means to retain the cover closed.
7. The combination of a casing, a movable arm, a shaft supporting said arm and projecting through the casing, a contact carried by said arm, a series of contacts to coact with the first named contact, resistance material in circuit with said series of contacts, a block carried by said shaft without the cas-
- ing, an arm pivoted upon said block and provided with a brake shoe, and means coactive between said arm and block for retaining the arm in set position.
8. The combination of a casing, a movable arm, a shaft supporting said arm and projecting through the casing, a contact carried by said arm, a series of contacts to coact with the first named contact, resistance material in circuit with said series of contacts, a block carried by said shaft without the casing, an arm pivoted upon said block and provided with a brake shoe, and screws carried by said block adapted to coact with said arm on opposite sides of its pivot to retain the arm in set position.

Signed at New York city, in the county of New York, and State of New York, this 8th day of July, A. D. 1915.

OSCAR I. JUDELSHON.
